UNITED STATES PATENT OFFICE.

JOSEPH CHIODO, OF MINNEAPOLIS, MINNESOTA.

TRAMMEL.

1,300,122.

Specification of Letters Patent.

Patented Apr. 8, 1919.

Application filed May 25, 1918. Serial No. 236,628.

To all whom it may concern:

Be it known that I, JOSEPH CHIODO, a citizen of the United States, residing at Minneapolis, in the county of Hennepin and State 5 of Minnesota, have invented new and useful Improvements in Trammels, of which the following is a specification.

This invention relates to trammels especially adapted to be used for drawing 10 ellipses and it consists in the novel features hereinafter described and claimed.

An object of the invention is to provide an instrument of the character stated which is of simple structure and which may be 15 readily used for accurately establishing the point upon a field through which the bounding line of an ellipse passes.

With this object in view the trammel comprises a frame having an arcuate side portion and a straight side portion which describes the chord of the arc of the arcuate portion. Three legs are pivotally connected together at one end and at a point exactly 20 midway between the ends of the straight side of the frame and a handle is mounted 25 upon the pivot which connects the legs together. Set screws are provided for fixing the legs with relation to the arcuate portion of the frame. The two outer legs are of the 30 same length and cannot be extended or elongated. The third intermediate leg is longitudinally extensible and may be lengthened or shortened as conditions will require.

In the accompanying drawing:-

Figure 1 is a side view of the trammel; Fig. 2 is an edge elevation of the trammel;

Fig. 3 is a perspective illustration of the manner in which the instrument is operated.

The trammel comprises a frame which 40 consists of a straight side 1 and an arcuate side portion 2. The side 1 describes the chord of the arc of the side 2. A pivot 3 is mounted on the side 1 at a point exactly 45 midway between the ends of the side portion 2. A handle 4 is mounted on the pivot 3. Legs 5, 6 and 7 are pivotally connected with each other by means of the pivot 3 and the legs are provided with set screws 8, 9 and 10 respectively which are adapted 50 to engage the arcuate portion 2 whereby the legs 5, 6 and 7 may be fixed at adjusted positions with relation to the frame. The outer legs 5 and 7 of the set of legs are not susceptible of being adjusted longitudinally but the intermediate leg 6 may 55 be longitudinally extended. To accomplish

this the leg 6 is composed of two sections. The upper section is tubular and provided with a set screw 11 which engages the shank 12 of the lower section and the said shank 60 is received in the tubular portion of the upper section of the leg 6.

Consequently it will be seen that all of the legs may be adjusted along the arcuate portion 2 of the frame and by tightening 65 the set screws 8, 9 and 10 they may be secured at the adjusted positions. Furthermore the intermediate leg may be extended longitudinally or contracted; therefore the points of the legs may be positioned at different 70 distances from the pivot 3.

As hereinbefore stated the instrument is adapted to be used for drawing or describing ellipses and the outer legs 5 and 7 may be spread a sufficient distance apart and the 75 intermediate leg may be positioned at a desired point between the outer leg and may be extended or contracted as conditions will require.

In this way the instrument is operated 80 to delineate an ellipse, as shown in Fig. 3.

This will be better understood when it is stated that prior to using the trammel two axes must be drawn, as shown in Fig. 3. The size of the ellipse is determined by placing 85 limiting points on the axes of any desired distances from the center, and caution must be observed that the distances equal one-half of the width of the ellipse. In

using the device the thumb screws 8, 9, 90 and 10 are loosened to permit the legs 5, 6, and 7 to spread and move freely along the rail 1. This rail 1 serves as a guide to which the legs are securely held in their proper positions while the device is in use. 95

The leg 6 is adjustable lengthwise, and the point on said leg must be on the same plane as the points of the legs 5 and 7. The operator spaces with the two outer legs 5 and 7 the distance equal to one-half of the major 100 axis. He then fastens the leg securely to the rail 1. He next spaces with the legs the distance equal to one-half the minor axis. Then having placed the leg 6 at the proper distance from the outer leg he fastens the 105 leg 6 through the medium of the thumb screw 9 and extends the leg lengthwise until the point falls on the same plane as the points of the legs 5 and 7. It will be understood in this connection that the point 110 of the leg 5 takes positions on all points on the minor axis between the center and the

extremity and the point of the leg 6 takes all points on the major axis between the center and the extremity. The point of the third leg 7 being in a straight line to the points 5 of the legs 5 and 6 establishes the points through which the bounding line of the ellipse passes. These points are then connected with a French curve. It will be understood from this that my novel device 10 obviates the necessity of employing the inaccurate and slow straight edge.

Having described the invention what is claimed is:—

1. A trammel comprising a frame having 15 an arcuate side portion and a straight side portion, the straight side portion being a chord of the arc of the arcuate side portion, a pivot carried upon the straight side portion at a point exactly midway between the

ends of the arcuate portion, three legs mov- 20 ably mounted on the pivot and means for securing the legs at adjusted positions upon the arcuate portion of the frame.

2. A trammel comprising a frame having 25 an arcuate side portion and a straight side portion, the straight side portion being a chord of the arc of the arcuate portion, a pivot mounted upon the straight side portion at a point exactly midway between the ends of the arcuate portion, three legs mov- 30 ably mounted on the pivot, means for securing the legs at adjusted positions upon the arcuate portion, the outer legs being non-extensible and the intermediate leg being longitudinally extensible.

In testimony whereof I affix my signature.

JOSEPH CHIODO.
